UNITED STATES PATENT OFFICE.

HENRY C. SWAN, OF OSHKOSH, WISCONSIN.

DESIGN FOR A STEP-PAD.

SPECIFICATION forming part of Design No. 24,306, dated May 14, 1895.

Application filed April 13, 1895. Serial No. 545,657. Term of patent 14 years.

To all whom it may concern:

Be it known that I, HENRY C. SWAN, of Oshkosh, in the county of Winnebago and State of Wisconsin, have invented and produced a new and original Design for Step-Pads, of which the following is a full, clear, and exact description, reference being had to the accompanying drawing, which shows in plan view a step-pad embodying my design.

10 The design consists in a step pad for vehicles, having a surface pattern comprising groups of three-sided pyramidal projections, which are distinct and are isolated laterally from each other, substantially as herein.

15 shown and described.

In the drawing, 2 represents the surface of a step-pad having on its surface a group of three-sided pyramidal projections 3.

I claim—

The design for step pads substantially as 20 herein shown and described.

In testimony whereof I have hereunto set my hand.

HENRY C. SWAN.
